RAILROAD CROSSING GATE AND SIGNAL

Martin Glowka, New York, N. Y.

Application May 18, 1940, Serial No. 335,903

6 Claims. (Cl. 246—294)

This application is a continuation-in-part of my earlier application Serial No. 149,590 filed June 22, 1937.

This invention relates to new and useful improvements in a signaling bell, alarm signal light, etc., and gate for railroad crossings.

The invention has for an object the construction of a device as mentioned which is characterized by the fact that it is a combination of a mechanical and an electric device.

More specifically, the invention proposes the provision of depressible members adjacent the rails of a railroad track system before and after a crossroad and adapted to be depressed by each wheel of a train passing over the track and associated with mechanism for operating the signal arm of a signal gate.

It is proposed to so arrange the device that as the train comes on to a crossing, as each wheel depresses the depressible member, the motion is transmitted mechanically or electrically to slowly and with an intermittent motion lower the gate. Thereafter, after the train has passed the crossing its wheels will engage the other depressible member, and as each wheel depresses it the movement will be communicated mechanically or electrically to progressively raise the gate until the gate is fully opened.

Furthermore, it is proposed to associate a bell mechanism, light mechanism and alarm device or devices with the device arranged to cause the same to operate during the lowering and raising of the gate.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a plan view of a portion of a railroad track system provided with a signaling bell, lamp and gate at a crossing constructed according to this invention.

Fig. 2 is a fragmentary enlarged vertical sectional view of a portion of Fig. 1 showing particularly the signal gate, the depressible members, and the operating mechanism.

Fig. 3 is a vertical sectional view on the line 3—3 of Fig. 1.

Fig. 4 is a vertical sectional view on the line 4—4 of Fig. 3.

Fig. 5 is a sectional view taken on the line 5—5 of Fig. 4.

Fig. 6 is a view similar to Fig. 5 but illustrating the position of the pawl and ratchet on the other side of the crossing.

Fig. 7 is a transverse horizontal sectional view taken on the line 7—7 of Fig. 2 but showing the gate lowered.

Fig. 8 is a fragmentary vertical sectional view taken on the line 8—8 of Fig. 7.

Fig. 9 is a fragmentary vertical sectional view taken on the line 9—9 of Fig. 7.

Fig. 10 is a horizontal sectional view looking in the direction of the line 10—10 of Fig. 2.

Fig. 11 is an enlarged horizontal view on the line 11—11 on Fig. 3.

Fig. 12 is an enlarged vertical sectional view on the line 12—12 on Fig. 2.

Fig. 13 is a perspective view of the top end of depressible member per se.

Fig. 14 is an elevational view of the toggle members per se.

Fig. 15 is an enlarged detailed view of the inner end of one of the toggle members per se.

Fig. 16 is a fragmentary sectional view similar to the disclosure of Fig. 2 but illustrating a modified construction.

Fig. 17 is a fragmentary enlarged vertical sectional view on the line 17—17 of Fig. 16.

The signal bell alarm and gate for railroad crossings, according to this invention, is used in combination with railroad tracks 10 and a cross road 11. For each of the tracks in one direction and for each of the tracks in the other direction, there is a signaling gate 12 at the crossing including towers 12^a and gate arms 12^b pivotally supported and adapted to be raised and lowered across the crossing 11. Depressible members 14 are arranged adjacent each track before and after the crossing and are adapted to be depressed by each wheel of a train passing over the tracks. A shaft 15 extends indirectly between the depressible members 14. A means is provided, operable by one of the depressible members for turning the shaft 15 in one direction. Another means is provided operable by the other of the depressible members for turning the shaft 15 in the other direction. A worm pinion 16 is mounted on the shaft 15 and meshes with a worm wheel 17 rotatively supported. A means is operable by the worm wheel 17 for raising the arm 12^b when turning in one direction and for lowering the arm 12^b when turning in the other direction.

The tower 12^a is of hollow construction and is formed with a slot 18 in its top end and one side. This slot is arranged to permit the arm 12^b

12^b to extend outwards and to move from a vertically raised position to a lowered position.

Each depressible member 14 comprises a pair of opposed toggle members 14^a which extend slightly upwards and upon which the flange 14^b of each of the wheels of a railroad train engage against and depress. Each depressible member 14 is also provided with a depressible rack member 14^c. The lower end of each rack member 14^c extends into a hollow casing 14^e and an expansion spring 20 operates between the bottom wall of the casing 14^e and the bottom end of the rack member 14^c to normally urge the depressible member into a raised position. When the wheel 15 of a train passes over it, it will be momentarily depressed but once the wheel passes it will be urged upwards into the raised position.

The toggle members 14^a have their outer ends pivotally supported adjacent the outside faces 20 of the tracks or blocks 14^x, and their inner ends extended upwards and overlapped. These overlapped ends are connected together by means of a roller 14^f (see Fig. 12) extended through elongated slots 14^{aa} formed in the inner ends of the 25 toggle members. The rack member 14^c has plates 14^g (see Fig. 13) secured to opposite sides of its upper end forming a bifurcated end between the fingers of which the inner ends of the toggle member 14^a are disposed. These toggle members 30 14^a and the plates 14^g are pivotally connected together by means of a pin 14^h extended freely through the plates 14^g and the roller 14^f. The slots 14^{aa} are so arranged that the inner ends of the toggle members 14^a will be caused to overlap 35 each other a greater amount when the depressible members 14 are depressed.

The casing 14^e has mounted on each of its sides a pair of spaced superimposed outwardly extending flange members. The bottom portion 40 of the casing 14^e is projected into an enlarged opening 71 formed in the earth therebeneath. A pair of plates 72 have their outer ends securely mounted on the surface of the earth on opposite sides of the opening 71, and their inner ends engaged between and securely attached to the adjacent faces of the flanges 70 for supporting the casing 14^e.

The shaft 15 has its intermediate area extended through the bottom of the tower 12^a, and 50 its ends extended into the casing 14^e. The means which is operable by one of the depressible members 14 to turn the shaft 15 in one direction comprises a gear 21 engaged by and meshing with the rack member 14^c. This gear 21 is located 55 within the casing 14^e and is loosely or freely mounted on the shaft 22 rotatively supported between the walls of the casing. A one way pawl 23 is resiliently mounted on the side of the gear 21 and engages a ratchet 24 fixed on the shaft 22. 60 There is a gear 25 also fixed on the shaft 22 which meshes with a gear 26 fixed on a shaft 27 rotatively supported between the walls of the casing 14^e. Bevel gears 28 connect the shaft 27 with the shaft 15. When the depressible member 65 14 at the left of Fig. 2 is depressed the shaft 15 will be driven in one direction and not in the other because of the action of the pawl 23, and the ratchet 24.

One side of the rack member 14^c is formed with 70 rack teeth 14^{cc} which mesh with the gear 21. A means is provided for holding the rack member 14^c in a position in which the rack teeth will continually engage the gear 21. This means comprises a flanged wheel 21^a which engages the side of the rack member 14^c opposed to the side

having the rack teeth 14^{cc}. The flanged wheel is rotatively supported upon a bracket 21^b extending from the wall of the casing 14^e.

The means operable by the other of the depressible members, namely, the depressible member at the right of Fig. 2 is identical in construction, except for the fact that it is provided with a pawl 23' (see Fig. 6) engaging a ratchet 24' set opposite to the corresponding pawl and ratchet 23 and 24. The arrangement is such that when 10 the depressible member 14 at the right is depressed the shaft 15 will turn in the opposite direction.

The worm wheel 17 is fixed upon the shaft 30 which is rotatively supported in the bottom of 15 the tower 12^a, and said shaft 30 is provided with a sprocket wheel 31 which is freely rotative thereon. This sprocket wheel 31 is engaged by a chain 32 which extends upwards through the tower 12^a and engages over a sprocket 33 rotatively supported by a shaft 34 disposed in the top of the tower 12^a. The sprocket 31 is indirectly driven by the shaft 30 through the medium of a slip clutch arrangement. This slip clutch arrangement includes disc 35 which is pinned on the 25 shaft 30. A friction clutch plate 37 is coaxially mounted on the shaft 30 and is longitudinally slidably supported thereon by a key 37^a.

The key 37^a is capable of transmitting rotations from the shaft 30 to the clutch plate 37. 30 A spring 36 is interposed between the disc 35 and the clutch plate 37 and forces the clutch plate 37 against the side of the sprocket 31. A collar 38^a is pinned upon the shaft 30 and engages the free face of the sprocket 31 for holding the sprocket 35 31 from sliding on the shaft 30. Rotations from the shaft 30 are transmitted to the disc 35 and the clutch plate 37, and if there is less than a certain load on the sprocket 31, the rotations will be transmitted to the sprocket 31. However, if 40 the sprocket 31 presents more than this certain amount of resistance, slipping will take place.

Adjustment screws 38 and 39 are associated with the top of the tower 12^a at locations to control the horizontal and vertical positions of the 45 arm 12^b. The adjustment screw 39 threadedly engages through a bracket 40 fixedly mounted on the top of the tower 12^a. This screw 39 is capable of being locked in various extended positions by a nut 41 threadedly mounted thereon 50 and abutting the lug 40. The screw 39 limits upward motion of the arm 12^b substantially to the vertical, though as illustrated in Fig. 2 the arm lacks about 15° from the true vertical direction.

The adjustment screw 38 is mounted on a 55 bracket 42 which is vertically, slidably and resiliently supported in the top of the tower 12^a. This bracket 42 has a vertical arm 42^a within the tower 12^a upon which the arm 12^b is pivotally supported by a pintle 43. The bracket 42 also 60 has a horizontal arm 42^b extending out from the slot 18 in the tower 12^a. The screw 38 threadedly engages through the horizontal arm 42^b and is adapted to limit downward motion of the arm 12^b to the horizontal position indicated by the dot 65 and dash lines in Fig. 2. A lock nut 41 threadedly engages the screw 38 and abuts the arm 42^b for locking the screw in adjusted positions.

The bracket 42 is vertically slidably supported by having lug portions 42^c which are slidably 70 mounted on vertical rods 43'. These vertical rods are supported on a bridge 44' stationarily mounted between opposite walls of the tower 12^a some distance below the bracket 42. Springs 44 are coaxially mounted on the rods 43' and act be- 75

tween the bridge 44' and the lugs 42^c for resiliently holding the bracket 42 in an elevated position.

A finger 46 is rigidly mounted to one of the links of the chain 32 and pivotally connects with a link 47 which in turn is pivotally connected with the arm 12^b at a point spaced from the pivot 43 and at a location substantially in line with the finger 46. These parts are so arranged that the link 47 and the finger 46 are capable of holding the arm 12^b in its raised position, and upon operation of the chain 32 are capable of pivoting the arm 12^b about the pintle 43 to lower the arm to its horizontal position.

In the horizontal position of the arm 12^b it 15 engages the adjustment screw 38 which is mounted on the bracket 42. Consequently, further operation of the chain 32, which will cause the finger 46 to move downwards, will act to lower the arm 12^b in its horizontal position from the 20 altitude indicated by the dot and dash lines in Fig. 2 to a lower position.

A brace member 49 is stationarily mounted on the inner face of one of the walls of the tower 12^a and extends along one side of the endless chain 32, and furthermore extends along one 25 side of the finger 46 for assisting in guiding these parts. The brace 49 acts in the nature of a reinforcing rail. Any tendency of the endless chain 32 in the vicinity of the finger 46 to belly 30 outwards will be arrested by the brace 49. Consequently, the endless chain is capable of efficiently transmitting upward and downward vertical movements to the finger 46 without much or any lateral distortion.

35 A star wheel 50 is fixed on the shaft 34 and controls an alarm system which includes an audible alarm 51 and a visual alarm 52. The star wheel 50 is cooperative with a spring contact 53 mounted on the inner wall of the tower 12^a and engageable selectively by the points of the star wheel as the star wheel turns. An electric circuit 54 is connected with the spring contact 53 and with the star wheel 50 and with the alarm 51 and the visual signal 52. The visual 40 signal 52 may comprise a lamp or other lightable signal, and preferably this signal should be mounted on the arm 12^b.

The alarm 51 may be mounted in the tower or adjacent the road 11, or wherever desired. The 45 adjustment screw 39 may be set so that when the arm 12^b is in its fully raised position, the circuit 54 will be opened between the star wheel 50 and the spring contact 53 so that the alarm and signal are not functioning. This adjustment is 50 easily possible, in that when the arm 12^b strikes the adjustment screw 39 it will serve to throw a load on the endless chain 32. Then the clutch plate 37 slips and the chain 32 no longer moves, and consequently the star wheel 50 is in a 55 stationary position. While the arm 12^b moves to its lowered position, the star wheel will have its points successively engage the spring contact 53 for periodically sounding the alarm devices.

Each gate 12 has a supplementary gate 12' 60 located on the opposite side of the track or tracks to which the gate or gates 12 are located. Each gate 12' is associated with a tower 12^a. The arrangement is such that the gate 12' will operate simultaneously with its complementary gate 12. The construction of the supplemental gate device 65 is identical to its complementary gate and therefore, the unitary action will readily be conceivable. In other words, when the arm 12^b of one of the signalling gates 12 is in its lowered position, the arm of the gate 12' of its complementary

signalling device will also be lowered and as the arm 12^b moves upwards the arm of the gate 12' will move correspondingly. Therefore when a train approaches the crossing 11 on any track it will operate the signalling and gate devices to 5 close the gates on the sides of the track system on the road 11.

In Figs. 16 and 17 a modified construction has been disclosed distinguishing from the prior form essentially in the way that the depressible members 14 operate the shaft provided with the worm pinion 16. Specifically, the worm pinion 16 is mounted on a rotative short shaft 15', which is rotatively mounted in the bottom of the tower 12^a. This shaft 15' is connected with an electric 15 motor 55 capable of rotating the shaft.

The depressible member 14 at the left has a depressible stem 14' which is connected with a piston 58 located within a cylinder 57. This piston is formed with several passages 59 which 20 have their upper ends normally closed by a loose valve disc 60. The top of the cylinder 57 is provided with a bleed air outlet valve 61 capable of permitting the slow escape of air from the top of the cylinder. The extreme top of the cylinder 57 25 has a cap shaped insulation member 62 mounted thereon capable of insulating the piston 58 from the cylinder 57 when the piston is in its fully raised position. An electric circuit 63 is connected with the electric motor 55 and with the 30 piston rod 56 and cylinder 57. When the piston 58 engages the cylinder walls 57 the circuit is completed. The lower portion of the cylinder 57 is formed with several air escape passages 57^a.

The depressible member 14 at the right is also 35 provided with a depressible stem 14' connected with the piston rod 56 of a similar device as that disclosed in Fig. 17. The cylinder is indicated by reference numeral 57 and the air passages at the bottom by 57^a. This electric control device is 40 connected in a circuit 63' which connects with the electric motor 55 in such a manner as to be capable of driving the motor in a reverse direction. The plates 72' in this form of the invention 45 are formed of insulation material for insulating the cylinder 57 from the earth. In other respects this form of the invention is similar to the previous form and similar parts may be identified by like reference numerals.

When the wheels 14^b of a train depress one or 50 the other of the depressible members 14 the depressible stem 14' will move a piston 58 downwards, closing a circuit between the piston and the cylinder 57. The electric motor 55 then functions to drive the shaft 15' in one or the other 55 direction depending upon which depressible member is depressed. This motion is transmitted to the worm pinion 16 and its worm wheel, etc., to drive the chain 32 in one or the other direction. After the wheel 14^b passes over a depressible 60 member 14 its spring 20 will move the same to its raised position which takes a short period of time due to the dash pot construction of cylinder 57, and this breaks the circuit by the piston 58 65 engaging the insulation material 62.

The operation of the signalling and gate device for railroad crossing, according to this invention, is as follows:

When a train approaches the crossing 11 its 70 wheels will ride over a depressible member 14 for example the one at the left of Fig. 2 or Fig. 16, depending upon the form of the invention being used. As each wheel passes over the depressible member it will be momentarily depressed or depressed until the train passes depending upon the 75

dash pot action of cylinder 51, and then be raised by the spring 20. This action of the depressible member will be transmitted indirectly to drive the worm pinion 16 which will indirectly transmit the motion to the arms 12^b and 12'. These arms will be lowered from their vertical positions to their horizontal positions, and after reaching their horizontal positions will move further downward in the horizontal positions.

10 With this arrangement persons are given ample warning at the cross road 11. First their attention will be attracted to the arms which are moving from their vertical to their horizontal positions. However, during this period persons, wagons, automobiles, and the like, caught between the tracks may readily scurry to safety on either side of the tracks. It is only after the arms 12^b and 12' reach their horizontal positions that they start moving downward to a relatively low position so as to prevent persons, automobiles, etc., outside the tracks from entering upon the tracks during this period. This permits a train to pass.

15 Simultaneous with the lowering of the arms 12^b and 12' the points of the star wheel 50 will intermittently contact with the contacts 53 and operate the circuit 54 for intermittently ringing the alarm 51 and operating the visual signal 52.

20 After the train has passed the crossing 11 and its wheels run over the depressible member 14 at the right of Fig. 2 or Fig. 16, the gate arms 12^b and 12' will be raised gradually indirectly by the depressions of the depressible member. First they will move upwards in their horizontal positions and then they will pivot to vertical positions.

25 It is to be understood that the electric circuit may be connected to the usual 110 volt supply or to storage batteries of suitable strength to operate the electrical devices used in this device.

30 While I have illustrated and described the preferred embodiments of my invention, it is to be understood that I do not limit myself to the precise constructions herein disclosed and the right 35 is reserved to all changes and modifications coming within the scope of the invention as defined in the appended claims.

Having thus described my invention, what I claim as new, and desire to secure by United 40 States Letters Patent is:

1. In a railroad crossing gate and signal, a tower, a sprocket wheel rotatively mounted in the top portion of said tower, a sprocket wheel rotatively mounted in the bottom portion of said tower, an endless chain engaging over said sprocket wheels, means controlled by an approaching train for driving said chain and having a slip device, a bracket vertically slidably mounted upon a bridging element fixedly mounted in the top portion of said tower, means for resiliently holding said bracket in a raised position, a signal arm pivotally supported on said bracket and extending from said tower and adapted to extend substantially vertically and to be lowered to a horizontal position, a stop on said tower for limiting said signal arm to its vertical position, a stop on said bracket for limiting said signal arm to its horizontal position, and means connected between said chain and signal arm for supporting the signal arm in its vertical position and being capable of moving said arm to its horizontal position as the chain moves to strike said stop controlling the horizontal position of said arm whereupon further movement 70 of said chain will cause said arm and bracket to

move vertically downwards relative to said tower.

2. In a railroad crossing gate and signal, a tower, a sprocket wheel rotatively mounted in the top portion of said tower, a sprocket wheel rotatively mounted in the bottom portion of said tower, an endless chain engaging over said sprocket wheels, means controlled by an approaching train for driving said chain and having a slip device, a bracket vertically slidably mounted upon a bridging element fixedly mounted in the top portion of said tower, said slidable bracket, comprising lugs formed on said bracket and slidably engaging rods extending vertically upwards from said bridging element, means for resiliently holding said bracket in a raised position, a signal arm pivotally supported on said bracket and extending from said tower and adapted to extend substantially vertically and to be lowered to a horizontal position, a stop on said tower for limiting said signal arm to its vertical position, a stop on said bracket for limiting said signal arm to its horizontal position, and means connected between said chain and signal arm for supporting the signal arm in its vertical position and being capable of moving said arm to its horizontal position as the chain moves to strike said stop controlling the horizontal position of said arm whereupon further movement of said chain will cause said arm and bracket to move vertically downwards relative to said tower.

3. In a railroad crossing gate and signal, a tower, a sprocket wheel rotatively mounted in the top portion of said tower, a sprocket wheel rotatively mounted in the bottom portion of said tower, an endless chain engaging over said sprocket wheels, means controlled by an approaching train for driving said chain and having a slip device, a bracket vertically slidably mounted upon a bridging element fixedly mounted in the top portion of said tower, said slidable bracket, comprising lugs formed on said bracket and slidably engaging rods extending vertically upwards from said bridging element, means comprising coil springs coaxially mounted on said rods and acting between said lugs and bridging element for resiliently holding said bracket in a raised position, a signal arm pivotally supported on said bracket and extending from said tower and adapted to extend substantially vertically and to be lowered to a horizontal position, a stop on said tower for limiting said signal arm to its vertical position, a stop on said bracket for limiting said signal arm to its horizontal position, and means connected between said chain and signal arm for supporting the signal arm in its vertical position and being capable of moving said arm to its horizontal position as the chain moves to strike said stop controlling the horizontal position of said arm whereupon further movement of said chain will cause said arm and bracket to move vertically downwards relative to said tower.

4. In a railroad crossing gate and signal, a tower, a sprocket wheel rotatively mounted in the top portion of said tower, a sprocket wheel rotatively mounted in the bottom portion of said tower, an endless chain engaging over said sprocket wheels, means controlled by an approaching train for driving said chain and having a slip device, a bracket vertically slidably mounted upon a bridging element fixedly mounted in the top portion of said tower, means for resiliently holding said bracket in a raised position, a signal arm pivotally supported on said bracket and extending from said tower and

adapted to extend substantially vertically and to be lowered to a horizontal position, a stop on said tower for limiting said signal arm to its vertical position, a stop on said bracket for limiting said signal arm to its horizontal position, and means connected between said chain and signal arm for supporting the signal arm in its vertical position and being capable of moving said arm to its horizontal position as the chain moves to strike said stop controlling the horizontal position of said arm whereupon further movement of said chain will cause said arm and bracket to move vertically downwards relative to said tower, said stops comprising screws threadedly mounted and means for holding said screws in various extended positions.

5. In a railroad crossing gate and signal, a tower, a sprocket wheel rotatively mounted in the top portion of said tower, a sprocket wheel 20 rotatively mounted in the bottom portion of said tower, an endless chain engaging over said sprocket wheels, means controlled by an approaching train for driving said chain and having a slip device, a bracket vertically slidably mounted upon a bridging element fixedly mounted in the top portion of said tower, means for resiliently holding said bracket in a raised position, a signal arm pivotally supported on said bracket and extending from said tower and adapted to extend substantially vertically and 25 to be lowered to a horizontal position, a stop on said tower for limiting said signal arm to its vertical position, a stop on said bracket for limiting said signal arm to its horizontal position, and means connected between said chain and signal 30 arm for supporting the signal arm in its vertical position and being capable of moving said arm to its horizontal position as the chain moves to strike said stop controlling the horizontal position of said arm whereupon further movement of

said chain will cause said arm and bracket to move vertically downwards relative to said tower, comprising a finger fixedly mounted on the side of said chain and pivotally connected with a link which in turn is pivotally connected with said 5 signal arm.

6. In a railroad crossing gate and signal, a tower, a sprocket wheel rotatively mounted in the top portion of said tower, a sprocket wheel rotatively mounted in the bottom portion of said tower, an endless chain engaging over said sprocket wheels, means controlled by an approaching train for driving said chain and having a slip device, a bracket vertically slidably mounted upon a bridging element fixedly mounted in the top portion of said tower, means for resilient holding said bracket in a raised position, a signal arm pivotally supported on said bracket and extending from said tower and adapted to extend substantially vertically and 20 to be lowered to a horizontal position, a stop on said tower for limiting said signal arm to its vertical position, a stop on said bracket for limiting said signal arm to its horizontal position, and means connected between said chain and signal 25 arm for supporting the signal arm in its vertical position and being capable of moving said arm to its horizontal position as the chain moves to strike said stop controlling the horizontal position of said arm whereupon further movement 30 of said chain will cause said arm and bracket to move vertically downwards relative to said tower, comprising a finger fixedly mounted on the side of said chain and pivotally connected with a link which in turn is pivotally connected with said 35 signal arm, and a brace mounted upon said tower and extending along a portion of said endless chain for holding said chain from buckling in the vicinity of said finger.

MARTIN GLOWKA. 40
